(57) **CLAIM**

The ornamental design for an electronic device, as shown and described.

DESCRIPTION

FIG. 1 is a perspective view illustrating an electronic device design according to one embodiment;

FIG. 2 is a front view illustrating an electronic device design according to one embodiment;

FIG. 3 is a back view illustrating an electronic device design according to one embodiment;

FIG. 4 is a side view illustrating an electronic device design according to one embodiment;

FIG. 5 is another side view illustrating an electronic device design according to one embodiment;

FIG. 6 is a top view illustrating an electronic device design according to one embodiment;

FIG. 7 is a bottom view illustrating an electronic device design according to one embodiment;

FIG. 8 is a perspective view illustrating an electronic device design according to one embodiment;

FIG. 9 is a front view illustrating an electronic device design according to one embodiment;

FIG. 10 is a back view illustrating an electronic device design according to one embodiment;

FIG. 11 is a side view illustrating an electronic device design according to one embodiment;

FIG. 12 is another side view illustrating an electronic device design according to one embodiment;

FIG. 13 is a top view illustrating an electronic device design according to one embodiment; and,

FIG. 14 is a bottom view illustrating an electronic device design according to one embodiment.

The broken lines shown immediately adjacent to the shaded areas in FIGS. 1 and 8 and also those shown immediately adjacent to the solid contour lines surrounding the unshaded region of the display window in FIGS. 8, 9, 13, represent the bounds of the claimed design, while all other broken lines are directed to environment and form no part of the claimed design.
